UNITED STATES PATENT OFFICE.

FRANK HEDLEY, OF YONKERS, AND JAMES S. DOYLE, OF MOUNT VERNON, NEW YORK.

COMBINED MULTIPLE-UNIT CAR-DOOR CONTROL SIGNALING AND ANNOUNCING SYSTEM.

Application filed July 25, 1919. Serial No. 313,406.

To all whom it may concern:

Be it known that we, FRANK HEDLEY and JAMES S. DOYLE, both citizens of the United States, and residents, respectively, of 5 Yonkers and Mount Vernon, county of Westchester, State of New York, have made a certain new and useful Invention in Combined Multiple-Unit Car-Door Control Signaling and Announcing System, of which 10 the following is a specification.

This invention relates to a combined multiple unit car door control signaling and announcing system for trains of cars.

The object of the invention is to provide a 15 combined multiple unit car door control signaling and announcing system for trains of cars which is simple and efficient.

A further object is to provide a combined 20 control signaling and announcing system of the nature referred to which will enable a single attendant at a control point or station to control the movements of all the doors of the train and of each car of the train and to announce the stations or other information, 25 instructions or directions to passengers in each car of the train.

A further object is to secure economy in the operation of subway, elevated and other 30 railway systems, without sacrificing anything of safety of operation, by placing the doors of, and street or station announcements for, all the cars of the train under the control of a single attendant.

Other objects of the invention will appear 35 more fully hereinafter.

The invention consists substantially in the construction, combination, location and relative arrangement of parts and circuit connections, all as will be more fully herein-after set forth, as shown in the accompanying drawings and finally pointed out in the appended claims.

In the drawings,

Figs. 1 and 1^a are views in circuit diagram showing the multiple unit car door control part of the combined system constituting our invention.

Figs. 2 and 2^a are similar views showing the signaling part of the system.

Figs. 3 and 3^a are similar views showing the announcing part of the system.

Figs. 4 and 4^a are similar views showing a modified announcing arrangement.

We have shown the door controlling, the 55 signaling and the announcing circuit ar-

rangements in separate views merely for clearness of illustration and to avoid the confusion and complexity incident to showing them in the same view, but it is to be understood that in the practical application of our invention the various circuit arrangements are all to be employed on each car of the train.

Referring first, to Figs. 1 and 1^a, showing the door control part of the system, it is to be assumed that the station or point of control of the doors, signal and announcing devices is to be located at A. This station

may be at any convenient or desired point on any car of a train of cars. In practice

where a train of ten cars, for example, is to be operated a convenient control point or station will be at the adjacent ends of the fifth and sixth cars of the train, that is, at the mid-length point of the train. At this

station are located four series of contacts under the control of a single attendant, two of the series respectively controlling circuits required for the door opening and closing operations for all the cars at one

side of the control station, and the other two series of contacts performing the same function for all the cars at the other side of the control station. In the case of a ten

car train each group of five cars will require five train wires for controlling the closing

movements of the doors and five for controlling the opening movements of the doors

on one side of the cars, where separate opening and closing magnets are employed

for controlling the door operating motors. For convenience and simplicity of illustration only the circuits concerned in the door operations on one side of the cars is shown.

Consequently the train wires 5, 6, 7, 8, 9, we

will call the door closing circuit wires, and the train wires 10, 11, 12, 13, 14, we will call

the door opening circuit wires. The contacts 15, 16, 17, 18, 19, 20, 21, 22, 23, 24, respectively, control the connection of these

train wires to a source of current through a train wire 25, which is connected to trolley, battery, or other current source, as indicated at 26.

Ordinarily there are three doors, 27, 28, 29, on each side of each car, and a motor (not shown) to operate each door, and an opening magnet 30, and a closing magnet 31 for each motor. A door opening relay switch magnet 32 and a door closing relay

switch magnet 33 is located on each car, for the doors on each side of the car. The magnets 32, 33, on each car are connected to the train line wires corresponding to that car. The relay magnets 32, 33, respectively, control switches 34, 35, for closing the circuits of the opening and closing magnets 30, 31.

It is to be understood that each group of cars in the train, the doors of which are to be controlled from the control station, is equipped with the circuits, relay magnets, switches and opening and closing magnets above described, the control of which is to be effected at the control station, although we have described above the arrangement for only one group of cars.

The operation will now be clear. When the train arrives at a station the attendant at the control point or station will successively, or in any desired order, or simultaneously, close the contacts 20, 21, 22, 23, 24, to the current supply conductor 25. For example, suppose contact 20 is closed. Thereupon circuit is completed from conductor 25 to train wire 14 through magnet 32 to ground at 36. The resulting energization of magnet 32 causes switch device 34 to close. Thereupon circuits are completed from current supply, wire 25, simultaneously through the car wires 37, 38 and 39, and the opening magnets 30 to ground at 40, and hence all the doors on that car will be simultaneously moved to open position. In like manner the closing of contact 21 will cause the same operations to take place on the next car of the group, and so on. The closing of contact 15 to current supply wire 25, will cause the circuit of relay magnet 33 to be closed to ground at 41, thereby causing switch 35 to close and hence causing car circuits to be completed from current supply wire 25 through the door motor closing magnets 31 to ground at 40, and hence causing all the doors on that car to simultaneously close. In like manner, the closing of the contact 16 at the control station will energize the closing of the circuit of relay magnet 33 on the next car, resulting in the same operation taking place on that car, and so on throughout the entire group of cars.

In identically the same manner the operations above described are carried out in the other group of cars which are controlled from the same control point or station.

If desired, and in order to secure safety of operation auxiliary switches indicated at 45, 46, may be respectively associated in auxiliary circuits 47, 48, through the opening and closing magnets 30, 31, and these switches 45, 46, may be automatically controlled in any desired manner. For example the switch 45 may be closed automatically when a door, in closing, encounters an obstruction, in the manner illustrated for

example in our copending application Serial No. 596071, filed June 17, 1921, or in accordance with the electric control disclosed in Patent No. 1,300,781, April 15, 1919, to Rowntree. In our present application the auxiliary circuit through the opening magnet 30 of that door is completed and causes the actuating motor to open the door, thereby averting accident or injury to a passenger who might be in the path of the closing movement of the door. In similar manner the switch 46 may be operated in case it is desired to close the door by hand in advance or independently of the closing action of the motor which effects the closing movements of that door. In such case an auxiliary circuit through the closing magnet 31 will be closed and hence the motor will be operated in closing direction to complete the closing movement of the door. Any desired or known type of automatic switch as the automatic switch (29 or 30) of Patent No. 1,300,781 to Rowntree may be used for the auxiliary switches 45 and 46.

In a control system above described it is desirable that the attendant at the control station as well as the motorman at the front end of the train be kept informed whether or not any door throughout the train is open so that proper precaution be taken to avoid accident or injury through the premature starting of the train by the motorman, as well as to call attention of the control attendant to any oversight or neglect in manipulating a control contact. Such a signal or indicating arrangement is particularly desirable and necessary in conjunction with the control system above described.

In Figs. 2, 2^a, we have shown a simple and efficient signal system consisting of a train wire 50, plugged in to trolley, battery, or other current source 51, at, say the rear end of the train or group of cars, as indicated at 52. On each car is located a relay magnet 53, which when energized closes a switch 54 in the train line wire 50. If the magnets 53 on all the cars are energized the switches 54 will be closed throughout the train to close a circuit through the motorman's signal device 55, such as a lamp, for example, and the lighting up or flashing of this lamp will indicate to the motorman that it is safe to proceed, and he should not start the train till he receives the signal. When the circuit of magnet 53 is broken a switch device 56 is closed. This device is arranged in the car circuit 57 of signal devices such as lamps 58 situated in convenient positions on the car, to be observed or seen by the attendant at the control station. The switch device 56 also closes a car circuit 59. This circuit includes in series therein door switches indicated at 60, and also the magnet 53. The door switches 60 are adapted to be closed

only when their respective doors are closed, so that if any door on any car is open the circuit of magnet 53 on that car is open, the switch 54 on that car is open, and the switch 56 on that car is closed, and consequently the signal devices 58 are flashed, and the motorman's signal device 55 is out of action. When all the doors on the train are closed the circuits of the magnets 53 are completed, thereby closing the switches 54 and opening switches 56. This closes the motorman's signal circuit and opens the car signal circuits, and hence it is safe to proceed with the train.

In order that the attendant at the control station may announce stations, or give directions or instructions to passengers in the remote cars under his control, we provide a loud speaking telephone system consisting of train circuits 61, 62, and car circuits. In the car circuits 63, 64, are switches 65, 66. In the circuits 63, 64, on each car is connected a telephone transmitter 67 and a loud speaking telephone receiver 68. A switch 69 is arranged to connect each car circuit 64 to the train wire 62. A battery 70 and primary 71 of a transformer are arranged in the circuit of the transmitter 67 on each car. Connected across the car circuit 64 and the train circuit 61 on each car is the secondary of the transformer 71 on that car. The loud speaking telephones 68 are connected across the line circuits 61, 62.

The operation of the announcing system is as follows, assuming the control station to be located at A, Fig. 3. The attendant will close the switches 65, 66 and 69, and will talk into the transmitter 67, making the desired announcement. This will cause variations in current flow in the circuit containing the telephone 67, the battery 70, and the primary of the transformer 71, resulting in corresponding telephonic currents being set up in the circuit of the secondary of the transformer 71. This secondary being connected across wires 64, 61, and the switch 69 being closed, the telephonic currents will be supplied to all the loud speaking telephones 68 which are connected across the train wires 61, 62, in parallel, and hence will deliver the message to the various cars of the group.

An announcing system similar to that above described is shown in Figs. 4 and 4^a, except that two transmitters are shown at each end of each car either one of which may be employed by the attendant.

A combined door control signal and announcing system of the nature above described enables trains of any desired number of cars, say up to ten, to be operated safely and without loss of time by only two attendants, the motorman and the one to effect the desired control operations, thus accomplishing an enormous saving of ex-

pense and economy in salaries or wages, over present methods of train operation.

Many modifications and changes in detail will readily occur to those skilled in the art without departing from the spirit and scope of our invention as defined in the claims. Having set forth therefore the objects and nature of our invention and having shown and described a system illustrative of the principles thereof, what we claim as new and useful and of our own invention, and desire to secure by Letters Patent, is,—

1. In an electrically controlled multiple unit car door control system, and in combination with the cars of a train and electrically controlled devices for controlling the opening and closing movements of the doors of each car of said train, a circuit for each of said devices, means located at one point in the train for selectively controlling the circuit of all of said devices, additional circuits and means for causing said devices to function independently of the main circuit. 80

2. In electrically controlled announcing, signaling, and multiple unit car door control systems, and in combination with the cars of a train, an electrically controlled device for controlling the opening movements of all of the doors on a car, a circuit for controlling said device, and means for controlling said circuit. 90

3. In an electrically controlled announcing, signaling, and multiple unit car door control system, and in combination with the cars of a train, an electrically controlled device for controlling the closing movements of all of the doors on a car, a circuit for controlling said device and means for controlling said circuit. 100

4. In an electrically controlled announcing, signaling multiple unit and car door control system, and in combination with the cars of a train, an electrically controlled device for controlling the closing movements of all of the doors on a car, a circuit for controlling said device, means for controlling said circuit, an auxiliary circuit for controlling said device, and means independent of said circuit controlling means for controlling said auxiliary circuit. 105

5. In an electrically controlled announcing, signaling, and multiple unit car door control system, and in combination with the cars of a train, an electrically controlled device located on each car for controlling the closing movements of all of the doors on each car, a separate circuit controlling each said device, and means located at a single station for controlling all of said devices. 120

In testimony whereof we have hereunto set our hands on this 22d day of July A. D. 1919.

FRANK HEDLEY.
JAMES S. DOYLE.
